UNITED STATES PATENT OFFICE.

GEORGE L. HALL, OF NEW YORK, N. Y.

INSULATED RAIL-JOINT.

SPECIFICATION forming part of Letters Patent No. 784,741, dated March 14, 1905.

Application filed January 9, 1904. Serial No. 188,305.

To all whom it may concern:

Be it known that I, GEORGE L. HALL, a citizen of the United States of America, residing in the borough of Brooklyn, city of New York, county of Kings, and State of New York, have invented certain new and useful Improvements in Insulated Rail-Joints, of which the following is a specification, reference being had therein to the accompanying drawings.

10 My invention relates to joints between adjacent rails of a railway and to the insulation of one rail from the rail adjacent to it; and its object is to provide an all-metal joint having base-support in which only one of the rail 15 ends need be insulated from the metal parts crossing the joint.

To this end my invention consists of means whereby one of the rail ends is insulated from all parts of the joint which might electrically 20 connect it with the other rail end.

I hereinafter describe a rail-joint embodying my invention and then point out the novel features in the claims, having reference to the accompanying drawings, in which similar 25 numerals of reference indicate similar parts throughout the various views, of which—

Figure 1 is a plan view. Fig. 2 is a section on the line 2 2 of Fig. 1. Fig. 3 is a section on the line 3 3 of Fig. 1, and Fig. 4 is a view of 30 a modification. Fig. 5 is a side view of the modification shown in Fig. 4. Fig. 6 is a view similar to Fig. 1, showing a modification. Fig. 7 is an enlarged detail view of a modification, and Fig. 8 is an enlarged detail view of the 35 washer 14' shown in Fig. 6.

1 represents a rail end electrically insulated from those parts of the joint that might otherwise electrically communicate with the other or adjacent rail end, 2.

40 3, 4, and 5 indicate members of a shoe-angle on one or preferably the out side of the joint. 20 is an angle-iron or metal band on the other or in side of the joint. The chair or shoe is insulated from the rail end 1 by insulating material 6, such as fiber, and the angle-iron or metal band 20 is insulated from the rail end 1 by insulating material 7.

8 and 9 are filling-pieces to compensate, re-

spectively, for the insulating parts 6 and 7. Of course it will be understood that I do not 50 limit myself to this method of compensating for the space occupied by the insulating material 6 and 7; but the method shown is a convenient and cheap manner of accomplishing the desired result. For instance, the shoe or 55 chair and the angle-iron or metal band might be made of thicker material at one end than at the other.

10 and 11 are bolts for securing the parts of the joint together. The bolts 10, passing 60 through the rail end 1, are insulated from the chair or shoe and the angle-iron or metal band by the well-known insulating-washers 12 and bushing 13.

14 indicates washers for protecting the insulating-washers 12.

It is often desirable to use instead of square-headed bolts 10 and 11 (shown in Figs. 1 to 3) bolts having an oval-shaped neck like those shown at 10' and 11' in Figs. 4 and 6. The object of using bolts having oval-shaped necks is to render it unnecessary to use an additional wrench to prevent the bolt turning as the nut is screwed up, and of course it will be understood that a stationary part must be provided with 75 which the oval-shaped neck of the bolt may mesh. I therefore provide a washer 14', as shown in Fig. 6, including at least two of the bolts, said washer 14' being provided with oval-shaped holes for the necks of the bolts, as 80 shown in Fig. 7. Of course I do not limit myself to an oval-shaped neck, as it will be readily understood that any other shape than round would answer the same purpose. It will also be understood that I do not limit myself to a joint having one chair in combination with an opposite band or angle-iron, as the well-known construction of two opposite chairs or a chair with two opposite bolt-plates might be used. In Figs. 4 and 5 I have shown such 90 a modification of my invention, in which 3', 4', and 5' indicate the members of the opposing chairs and bolt-plates. I sometimes provide additional strength to such a joint by means of lugs 21, depending from the chairs, 95 in combination with bolts 22.

15 indicates insulating end posts, which should be used where the rails are not separated by an air-space.

What I claim, and desire to secure by Letters Patent, is—

1. In an insulated rail-joint the combination of two rail ends with a metal bridge-plate and opposing metal clamping-plates crossing the joint, said bridge-plate and clamping-plates 10 being in electric contact with one of said rails, insulating material between the other of said rail ends and said bridge-plate and clamping-plates, and means for holding said rail ends in alinement and out of contact with each 15 other.

2. In an insulated rail-joint the combination of a metal band or fish-plate crossing the joint with a plurality of bolts passing through said band and one of the rail ends, said bolts being provided with necks other than round, 20 and a washer adapted to include at least two of said bolts and provided with holes adapted to mesh with the necks of said bolts.

In witness whereof I have hereunto set my hand this 7th day of January, 1904.

GEO. L. HALL.

In presence of—

ALOYSIUS E. TENHAGEN,
J. F. BOUDREAU.
